LINOLEUM OR SIMILAR ARTICLE

William Rowe, Lewiston, and George Nobis, Readfield,
Maine, assignors to Bonafide Mills, Inc., New York,
N. Y., a corporation of Maine

Application January 19, 1954, Serial No. 28,578

Term of patent 14 years

(Cl. D92—17)

To all whom it may concern:

Be it known that we, William Rowe, a citizen of the United States of America and a resident of Lewiston, Androscoggin County, State of Maine, and George Nobis, a citizen of the United States of America and a resident of Readfield, Kennebec County, State of Maine, have invented a new, original, and ornamental Design for Linoleum or Similar Article, of which the following is a specification, reference being had to the accompanying drawing, forming a part thereof, of which the single figure is a top plan view of the linoleum or similar article showing our new design.

We claim:

The ornamental design for a linoleum or similar article, as shown.
